UNITED STATES PATENT OFFICE.

JOSEPH A. KENNEDY, OF KIONA, WASHINGTON.

BICYCLE HAND-GRIP.

1,303,803.

Specification of Letters Patent. Patented May 13, 1919.

Application filed May 4, 1917. Serial No. 166,417.

To all whom it may concern:

Be it known that I, JOSEPH A. KENNEDY, a citizen of the United States, residing at Kiona, in the county of Benton and State 5 of Washington, have invented certain new and useful Improvements in Bicycle Hand-Grips; and I do hereby declare the following to be a full, clear, and exact description of the invention, such as will enable others 10 skilled in the art to which it appertains to make and use the same.

This invention relates to hand grips for bicycles, motorcycles or like vehicles, and the primary object of the invention is to 15 provide a resilient hand grip, which is constructed, so that it will not break at the outer end of the handle bar, upon which it is mounted, thereby providing a durable and relatively inexpensive hand grip.

20 A further object of this invention is to provide a hand grip as specified, the outer casing of which is constructed of any suitable type of resilient material, such as layers of fabric coated with rubber, and 25 which has a coil spring positioned interiorly thereof, which coil spring is constructed of tapered wire, having the end of the spring which is next to the end of the handle bar of greater strength than the outer end of 30 the spring.

With the foregoing and other objects in view this invention consists in such novel features of construction, combination and arrangement of parts as will be hereinafter 35 more fully described, illustrated in the accompanying drawing and claimed.

In describing the invention in detail reference will be had to the accompanying drawings wherein like characters designate 40 like and corresponding parts throughout the several views, and in which:

Figure 1 is a longitudinal section through the improved hand grip, and

Fig. 2 is a cross section in the line 2—2 45 of Fig. 1.

Referring more particularly to the drawing, 1 designates a fragment of a handle bar of an ordinary bicycle, motorcycle, or the like, which has a hand grip generally 50 indicated by the numeral 2 mounted thereon. The hand grip 2 comprises an outer casing 3 which is constructed of layers of fabric, with an outer casing or coating of rubber or analogous resilient material.

55 The casing 3 extends over the end of the handle bar 1, and it has a collar 4 positioned

therein. The collar 4 is constructed of sheet metal, and has a partition or plate 5 extending across the same, which plate is adapted for abutment against the end of the 60 handle bar 1.

The plate 5 is formed intermediate the ends of the collar 4, so that a portion of the collar will extend about the end of the handle bar 1. A metallic cap 6 is positioned 65 within the outer end of the casing 3. A spiral spring 7 is mounted within the casing 3, and is constructed of tapering wire, which is coiled to form the spring and has its heavier end positioned inwardly, thereby 70 providing a spring, which is of greater strength at its inner end than at its outer end, so as to eliminate the liability of cracking or breaking of the casing 3 at the end of the handle bar 1 due to excessive bending 75 thereof at its line of juncture with the bar. The inner end of the spring 7 is coiled to form a flat coil as clearly shown at 8 in Fig. 2 of the drawing, and it has its end secured to the plate 5, by a rivet, bolt or 80 analogous fastening device indicated at 9. The flat coil 8 of the spring abuts the outer face of the plate 5.

In reducing the invention to practice, certain minor features of construction, combination and arrangement of parts may necessitate alterations to which the patentee is entitled provided such alterations are comprehended within the scope of what is claimed. 90

What is claimed is:—

1. In a hand grip structure, an outer casing constructed of resilient material having one end closed, a spiral spring positioned within said casing, said spring being constructed of tapered wire coiled to form the spring and having its heavier end positioned inwardly from the closed end of the casing. 95

2. In a hand grip structure, an outer resilient casing, a metallic collar positioned within said casing and adapted to be secured on the end of a handle bar, a plate extending transversely of said collar, a metallic cap positioned in one end of said casing, and a spiral spring positioned within 100 said casing, said spring being constructed of tapered wire coiled to form the spring and having its heavier end positioned within said collar, the inner end of said spring being connected to said plate. 105

3. The combination with a handle bar, of a flexible tubular casing closed at its outer 110

end and having its inner end fitting snugly about the end portion of said bar, a spirally coiled spring positioned within said casing, and an abutment member positioned within 5 the casing and engaging the end of the bar, said spring being confined between the outer end of the casing and the abutment member, the spring increasing uniformly in thickness from its outer end so as to offer uniformly

increasing resistance to bending of said casing, from the outer end thereof.

In testimony whereof I affix my signature in presence of two witnesses:

JOSEPH A. KENNEDY.
